FOREIGN PATENT DOCUMENTS

CN 307385994 * 6/2022

Primary Examiner — T Chase Nelson*Assistant Examiner* — Kelly L Gross(74) *Attorney, Agent, or Firm* — Dragon Sun Law Firm,
PC; Jinggao Li; Nathaniel Perkins(57) **CLAIM**

The ornamental design for an earplug, as shown and described.

DESCRIPTION

FIG. 1 is a front, top perspective view of an earplug showing my new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the earplug that form no part of the claimed design.
